United States Patent Office

Des. 185,519
Patented June 16, 1959

185,519

MANICURING IMPLEMENT

Arnold M. Thompson, Wheaton, Ill., assignor to Thompson Tool and Manufacturing Co., Franklin Park, Ill., a corporation of Illinois

Application August 4, 1958, Serial No. 52,048

Term of patent 14 years

(Cl. D86—10)

Fig. 1 is a top perspective view of a manicuring implement embodying my design;

Fig. 2 is a front elevational view;

Fig. 3 is a side elevational view;

Fig. 4 is a top plan view; and

Fig. 5 is a bottom plan view.

I claim:

The ornamental design for a manicuring implement substantially as shown.
